(57) **CLAIM**

The ornamental design for a seat, as shown and described.

DESCRIPTION

FIG. 1 is a front right side perspective view of a first embodiment of a seat showing my new design;

FIG. 2 is a rear right side perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a top plan view thereof;

FIG. 8 is a front right side perspective view of a second embodiment of a seat showing my new design;

FIG. 9 is a rear right side perspective view thereof;

FIG. 10 is a front elevation view thereof;

FIG. 11 is a right side elevation view thereof;

FIG. 12 is a rear elevation view thereof;

FIG. 13 is a left side elevation view thereof; and,

FIG. 14 is a top plan view thereof.

The broken lines shown in the drawings illustrate portions of the article that form no part of the claimed design. The second embodiment is shown with symbolic breaks, and those portions of the article between the break lines form no part of the claimed design.

1 Claim, 14 Drawing Sheets
